CHAIN GUARD

Raymond U. H. Tegner, Lodi, Wis., assignor to
Amerock Corporation, Rockford, Ill.

Original design application Nov. 10, 1972, Ser. No.
305,567. Divided and this application Oct. 24,
1973, Ser. No. 409,240

Term of patent 14 years

Int. Cl. D8—07

U.S. Cl. D8—131

FIG. 1

FIG. 2

FIG. 5

FIG. 6

FIG. 3

FIG. 4

FIG. 7

FIG. 8

FIG. 9

FIG. 10

FIG. 11

FIG. 12

FIG. 13

FIG. 1 is a front view of a chain guard showing my new design and a keeper plate shown at the left and a base plate shown at the right.

FIG. 2 is a bottom view of the keeper plate.

FIG. 3 is a side view of the keeper plate as viewed from the left in FIG. 1.

FIG. 4 is a side view of the keeper plate as viewed from the right in FIG. 1.

FIG. 5 is a back view of the keeper plate.

FIG. 6 is a sectional view taken along the line 6-6 in FIG. 1.

FIG. 7 is a sectional view taken along the line 7-7 in FIG. 1.

FIG. 8 is a top view of the base plate shown in FIG. 1.

FIG. 9 is a bottom view of the base plate.

FIG. 10 is a side view of the base plate as seen from the right in FIG. 1.

FIG. 11 is a back view of the base plate.

FIG. 12 is a sectional view taken along the line 12-12 in FIG. 1.

FIG. 13 is a sectional view taken along the line 13-13 in FIG. 1.

The portions shown in broken lines form no part of the design.

This application is a division of my co-pending application Ser. No. 305,567, filed Nov. 10, 1972.

I claim:

The ornamental design for a chain guard, as shown and described.
